UNITED STATES PATENT OFFICE

HAROLD I. DYER, OF DETROIT, MICHIGAN, ASSIGNOR TO WILCOX-RICH CORPORATION,
A CORPORATION OF MICHIGAN

VALVE GRINDING MEANS

Application filed March 14, 1930. Serial No. 435,892.

Because the present invention relates particularly to an expedient favorable to a rapid and accurate production of any usual or special tappet valves, such as are currently provided in the engines of automotive vehicles and the like, it will be herein described with particular reference to valve grinding; and as applied to a grinding operation in which a valve head, of a usual "mushroom" type is centrally engaged by a fixed element while the valve is rotated by means of a chuck,—the valve stem being supported, near said head by a so-called "steady rest". The principles of the invention are, however, believed to render the same applicable also to certain "centreless" grinding operations in which steady rests are used and to the grinding of various objects in which importance attaches to accuracy of fit and to an avoidance of scoring opposite a steady rest.

On account of a known tendency of grinding operations, of the character referred to, to produce scoring effects in the region of contact of steady rests with valve stems, it has been customary to defer the so-called "finish-grinding" of stems until after the grinding of valve heads,—the stems being then brought to final size. But this sequence of steps, wherein the steady rest has engaged a comparatively imperfect surface during the grinding of the head, has necessitated a rather wide tolerance of imperfection in the grinding of the heads. It is a primary object of the present invention to effect such a simplification and improvement in valve grinding means and methods as shall obviate the mentioned scoring and thereby render it practicable both to finish-grind the stems in advance of the grinding of the heads and to substantially diminish the tolerance of error in the final grinding of either the peripheral portions or the seat portions of heads.

A preferred expedient by which the foregoing results are obtainable is surprisingly simple,—consisting essentially in the inter-

position of renewed portions of a suitable sheet material, such as paper of appropriate quality, between the steady rest and the valve stem. The scoring effects to be obviated have been found to result mainly from fragments 50 of steel, plating metal and/or abrasive material which become lodged upon the steady rest,—the hardness of the latter being such as to support them as if for a cutting effect; and the solution of the mentioned problem 55 has been found to lie in the interposition and repeated renewal of a suitable sheet material,—such as paper which is sufficiently hard firmly to support the valve stem and is nevertheless practically anti-frictional. It 60 should not adhere to the stem but should so yieldably support any small particles that may become interposed beneath the stem as to obviate scoring thereof.

To bring out the essential principles relied on, one of many simple means that may be employed for bringing fresh surfaces of paper, or a like low-friction web into a position between a steady rest and a valve stem is herewith illustrated; but the essentially 70 diagrammatic character of this illustration, and also the relative importance of the new method, as compared with any specific means for its execution, are especially emphasized; and other objects of the present invention 75 may be best appreciated from the following description of an illustrative embodiment thereof, taken in connection with the appended claims and the accompanying drawing.

Fig. 1 is, for the most part, an elevational view, a valve stem being shown as sectioned in a plane such as that suggested by line 1—1 of Fig. 2.

Fig. 2 is a plan view, taken substantially 85 as suggested by the arrow 2 of Fig. 1.

In Fig. 2, a valve V comprising a head H and a stem S is shown as disposed between a fixed bearing element B, centrally engaging the head H, and a rotated chuck C,—a grind- 90

er G being forwardly movable during its rotation relatively to said head, and a steady rest or a pair of steady rests R, R' being disposed beneath the stem S in proximity to the head H.

Although the opposite inclination and also any sharp corners or like parts of the terminal surfaces of the steady rest elements R, R' may be favorable to the removable retention of a sheet of paper P thereby during rotation of the stem S, any suitable means may be employed to contribute to the supply, support, tensioning and/or convenient removal of the paper P. This is shown as a continuous strip terminating in a roll P'; and this may be supported in any convenient way,—as from the steady rest element R. For the purpose last referred to, bracket elements 10, 10' are shown as provided with inwardly bent ends 11, 11', suitably spaced for engagement of the rest R,—one of a pair of bolts 12, 12' being shown as provided with a wing nut 13; and a bracket element or elements 10, 10' may support not only a pivot or bearing element 14 for the roll P', through or into which a core or plugs 15, 15' may extend in a known manner (the pivot element 14 being shown as retained by a removable cotter 16) but also with any suitable means for advancing or controlling the tension of the paper strip P. For the purpose last referred to, upwardly extending arms 17, 17' of the brackets 10, 10' may, for example, be provided with longitudinal slots 18, adapted to receive a transverse pressure-applying or strip-advancing element 19, if desired. The element 19 may have the form of a roller provided (preferably near the ends thereof, as at 20, 20') with slight projections adapted to engage the paper or other strip material, and also with means, such as a crank 21, for rotating said roller.

It should not be overlooked that advantageous effects may be obtained without the employment of any of the mechanical devices referred to, as by merely dropping a sheet of suitable paper or the like onto a steady rest in advance of the disposition of the valve stem thereon,—any angularity of the steady rest being favorable, by engagement of comparatively sharp corners 22 therewith, to the momentary retention of the paper, as the latter is depressed by the valve stem; but the described means are favorable to an avoidance of litter by the use of a continuous strip of the friction-obviating material; and, if desired, an end of the mentioned strip may be returned over or beneath the roll 19, or its equivalent, in such manner as to provide a loose protective loop over the stem S in the region of the rest or rests R, R'. The handle 21 of the roller 19 should be understood as merely suggestive of any desired mechanical means for advancing the paper P, in case this material is provided in strip form; but

it will be obvious that a slight pull upon the strip, as by a direct manual engagement thereof in the region of the steady rest R', may ordinarily be preferred to any use of more complicated means for the simple operation of advancing said strip.

It will be understood that, with a fresh surface of paper, or the like, interposed in the described manner, or in any preferred manner, between a stem which has been "finish-ground" and a steady rest, the grinding of the head may be promptly completed with a high degree of accuracy,—the deferred grinding of the stem being obviated; and the invention should not be understood to preclude either the finish-grinding of stems in an operation continuous with the rough grinding thereof or the adaptation of the mentioned web to an appreciable polishing effect.

The flexible sheet or strip of paper or other web employed should be neither so spongy as to defeat the function of the steady rest nor so hard as to exclude and elevate any particles received by said paper. Metallic foils or special fabrics are not known to possess any advantages commensurate with their higher cost; and it is suggested that in case a fine wire mesh is to be employed, it be first subjected to a heavy flattening pressure. No oleaginous, resinous or mineral additions to the cellulosic ingredients of a suitable paper are necessary; but the resiliency thereof may, if desired, be such as to separate an upper lap 23 from a lower lap 24, in case a loop is to be maintained in the paper strip without the use of special guides therefor. Such a loop should permit the free introduction and removal of valve stems; and, in order to gain a protective function from the upper lap and to obviate any dropping of particles therefrom onto unused portions of the strip, the direction of advance of said strip may be that indicated by the arrow 24'. Such a loop should permit the free introduction and removal of valve stems; and, in order to gain a protective function from the upper lap and to obviate any dropping of particles therefrom onto unused portions of the strip, the direction of advance of said strip may be that indicated by the arrow 24'. It will be understood, however, that the details referred to, as also the configuration of any non-rotary supporting means, such as a steady rest or rests, are relatively unimportant and subject to wide variation.

Although the foregoing description has included details of but one embodiment of the present invention, it will be obvious not only that features thereof might be independently employed but also that various modifications, additional to any suggested herein, might easily be devised by skilled workers, if informed of the foregoing,—all without departure from the scope of the present invention, as the latter is indicated in the following claims:

1. A valve grinding mechanism comprising means for supporting a valve in position for grinding, a pair of brackets secured to said means, a shaft secured to said brackets for rotatably supporting a continuous strip of low-friction web material and means includ-

ing a roll, having a plurality of engaging elements for moving said strip between the supporting means and the stem of the valve.

2. A valve grinding mechanism comprising means for supporting a valve in position for grinding, a pair of brackets secured to the means, a shaft mounted on the brackets for rotatably supporting a continuous strip of paper material and means having a plurality of projections engaging said strip material, for moving said strip material between the supporting means and the stem of the valve.
